Inventors

UNITED STATES PATENT OFFICE.

MAX PEÑA AND PATRICIO CRUZ, OF HEBBRONVILLE, TEXAS.

CLEANING APPARATUS.

1,231,936.

Specification of Letters Patent.

Patented July 3, 1917.

Application filed October 10, 1916. Serial No. 124,786.

To all whom it may concern:

Be it known that we, MAX PEÑA and PATRICIO CRUZ, both citizens of the United States, residing at Hebronville, in the county of Jim Hogg, State of Texas, have invented a new and useful Cleaning Apparatus; and we do hereby declare the following to be a full, clear, and exact description of the invention, such as will enable others skilled in the art to which it appertains to make and use the same.

The present invention relates to an apparatus for cleaning all kinds of receptacles and dishes, such as cuspidors and plates, and has for its object to provide a device of this character which embodies novel features of construction whereby such articles may be thoroughly and quickly cleaned with a minimum amount of labor, and without any unnecessary handling thereof.

Further objects of the invention are to provide a cleaning device of this character which is comparatively simple and inexpensive in its construction, which occupies but a small amount of floor space, which can be easily manipulated by a single person, and which quickly and thoroughly cleans the articles without any unnecessary handling thereof.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a side elevation of a cleaning apparatus constructed in accordance with the invention, the mop or swab member being shown as lowered into operative position, and portions being broken away and shown in section to illustrate more clearly the details of construction.

Fig. 2 is a similar view, the mop or swab member being shown as elevated into inoperative position.

Fig. 3 is an enlarged horizontal sectional view on the line 3—3 of Fig. 2.

Corresponding and like parts are referred to in the following description and indicated in all the views of the drawings by the same reference characters.

Referring to the drawings, which illus-

trate one possible embodiment of the invention, the numeral 1 designates a base which may be secured to the floor 2, or other horizontal supporting surface, in any suitable manner as by means of the screws 3. A tubular standard 4 projects upwardly from the base 1, having the lower end thereof threaded into the base, as indicated at 5. Collars 6 are fitted upon the standard 4 and clamped in adjusted positions thereon by set screws 7. Corresponding arms 8 project laterally from the collars 6 and terminate in guide eyes 9 which receive an upright shaft 10. This shaft 10 is parallel to the standard 4 and is slidable up and down through the guide eyes 9, the lower end of the shaft being provided with a cleaning swab or mop member 11.

A work supporting shelf 12 is arranged under the cleaning swab 11, being shown in the present instance as resting upon an annular bracket 13 which is clamped in some suitable manner, as indicated at 14, to the top of the base 1. The cuspidor 15, or other article to be cleaned, is designed to be placed upon the work supporting shelf 12 and thereby properly positioned directly under the cleaning swab 11. It may also be noted that the work supporting shelf 12 is provided with a drain opening 16, and that a bucket or other receptacle 17 for the collection of drippings is positioned under the work supporting shelf to receive the drippings from the said drain opening.

The tubular standard 4 is provided in opposite sides thereof with corresponding longitudinal slots 18, and a bearing member is slidable upon the standard, said bearing member being formed in complementary halves 19 which fit against opposite sides of the standard, each of the said halves being formed with an inwardly extending rib 20 which extends into one of the slots 18. It will also be observed that one of these ribs 20 is provided with projections 21 adapted to engage corresponding depressions 22 in the opposite rib to hold the two halves 19 of the bearing against relative vertical movement and lock them securely in proper relative position. A short horizontal shaft 23 extends through the bearing members 19 and is journaled therein, one end of the shaft being provided with a crank handle 24, while the opposite end thereof is provided with a beveled gear 25 which meshes with a corresponding beveled gear 26 on

the upright swab carrying shaft 10. The horizontal shaft 23 extends through the slots 18 of the standard 4, and nuts or collars 27 which are applied to the shaft serve to hold the bearing members 19 in operative position. Jam nuts 28 may be provided for locking the nuts 27 in position, and washers 29 may be interposed between the nuts 27 and the bearing members 19 to reduce the friction.

10 A coil spring 30 is arranged within the tubular standard 4 and interposed between the lower ends of the bearing members 19 and a suitable abutment such as the cross pin 31. This spring normally tends to slide the bearing members upwardly upon the standard 4, and it will be obvious that the swab 11 and upright shaft 10 will be carried upwardly with the bearing members, the 15 normal position of the parts being that indicated by Fig. 2. A handle 32 is mounted upon a cross bar 33 which extends transversely between the upright shaft 10 and the standard 4. The opposite ends of the cross 20 bar terminate in guide eyes 34 which slidably receive the standard and upright shaft, respectively, and a pair of set collars 35 are applied to the shaft 10 to engage opposite 25 sides of the eye 34 and lock the handle with the said shaft.

30 In the operation of the device the cuspidor 15 or other article to be cleaned is partially filled with water and placed upon the work supporting shelf 12. The handle 32 is then grasped by one hand and forced 35 downwardly to lower the cleaning swab 11 into operative position and bring it within the cuspidor, as indicated by Fig. 1, the bearing members 19 being simultaneously 40 moved downwardly against the action of the spring 30. The device is held in this position and the cleaning swab 11 rotated within the cuspidor by turning the crank handle 24. As soon as the mechanism is released 45 the cleaning swab 11 will be raised into inoperative position by the action of the spring 30. The cuspidor can then be removed from the work supporting shelf, and the drippings from the swab 11 will drain through 50 the opening 16 of the work supporting shelf into the bucket or receptacle 17. In this manner cuspidors and like articles can be thoroughly and quickly cleaned, and all unnecessary handling thereof is eliminated.

55 Having thus described the invention, what we claim as new and desire to secure by Letters-Patent is:—

1. A cleaning apparatus including a tubular standard provided with a longitudinal 60 slot, a bearing slidably mounted upon the tubular standard and formed with a rib which is received within the slot thereof to hold the bearing against rotation, a horizontal drive shaft journaled upon the bearing, arms projecting laterally from the

standard and terminating in guide elements, an upright shaft slidable within the guide elements and movable up and down with the bearing, gearing between the drive shaft and the vertical shaft, yielding means normally tending to move the bearing and vertical shaft upwardly, a cleaning swab applied to the lower end of the upright shaft, a work supporting shelf arranged under the cleaning swab, and a handle for moving the upright shaft downwardly to bring the cleaning swab into operative position.

2. A cleaning apparatus including a tubular standard provided with longitudinal slots, complemental bearing members applied to opposite sides of the standard and formed with ribs which project slidably into the slots thereof, a drive shaft extending through the slots of the standard and journaled in the bearing elements, means on the drive shaft for holding the bearing elements in operative position, yielding means for normally holding the bearing elements in raised position, an upright shaft carried by the standard and movable longitudinally up and down with the bearing elements, guide means for the upright shaft, gearing between the drive shaft and the upright shaft, a cleaning swab fitted upon the upright shaft, and means for lowering the upright shaft against the action of the yielding means.

3. A cleaning apparatus including a tubular standard having longitudinal slots in the sides thereof, complemental bearing members slidable upon opposite sides of the tubular standard and formed with ribs which are received within the slots thereof, one of the ribs being provided with positioning projections while the other rib is provided with depressions to receive the said 100 positioning projections, a drive shaft extending through the slots of the standard and journaled within the bearing members, collars upon the drive shaft for holding the 105 bearings in operative position, yielding means normally tending to slide the bearing members upwardly, an upright shaft carried by the standard and movable longitudinally up and down with the bearing 110 members, guide means for the upright shaft, gearing between the drive shaft and the upright shaft, a cleaning swab applied to the upright shaft, and means for moving the 115 upright shaft downwardly to bring the 120 cleaning swab into operation position.

4. A cleaning apparatus, including a tubular standard having longitudinal slots in the opposite sides thereof, complemental bearing elements slidable upon opposite sides 125 of the standard and formed with ribs which project into the slots, a horizontal drive shaft extending through the slots of the standard and journaled within the bearing elements, collars upon the drive shaft for 130

holding the bearing elements in proper position, a spring housed within the tubular standard and acting upon the bearing elements to hold them yieldingly in a raised position, arms projecting laterally from the standard and terminating in guide elements, an upright shaft slidable within the guide elements and movable with the bearing members, gearing between the drive shaft 10 and the upright shaft, a cleaning swab applied to the lower end of the upright shaft, a work supporting shelf arranged under the

cleaning swab, and a handle for moving the upright shaft downwardly to bring the cleaning swab into operative position. 15

In testimony whereof we have signed our names to this specification in the presence of two subscribing witnesses.

MAX PEÑA.
PATRICIO CRUZ.
